UNITED STATES PATENT OFFICE

WILLIAM S. HAWKINS, OF WASHINGTON, DISTRICT OF COLUMBIA

AUTOMOBILE SEAT CAPE

Application filed July 21, 1931. Serial No. 552,246.

The object of my invention is to provide a comfortable and efficient rumble seat cape for one or two persons that is wind, snow and rain proof.

5 A further object of my invention is to provide a cape of this character that may be conveniently carried in the car in a small package, and which may quickly and readily be assembled in position on the car, and the forward edge of which is adapted to be secured to the usual rain gutter in such manner as to not only utilize said gutter as a holding means but also to carry off rain water falling from the cape.

10 15 A further object of my invention is to provide means to prevent the entrance of wind, or rain, through the twin design by providing a closure for the unused opening in the cape.

20 25 A further object of my invention is to make it possible for four passengers to use a rumble seat car for touring irrespective of weather conditions; and with these and other objects in view my invention consists of the parts and combination of parts hereinafter set forth.

In the drawings:

Figure 1 is a side elevation of the rear end portion of a rumble seat automobile showing my invention in place and in use.

Figure 2 is a top plan view of the same.

Figure 3 is a vertical sectional view on the line 3—3, Figure 2.

35 Figure 4 is a perspective view of my improved cape detached and in extended position.

Figure 5 is a perspective view of a package with my improved cape enclosed therein.

40 Figure 6 is a detail section showing more particularly the construction of the spring clips and their mode of application to the apron and gutter.

The reference numeral 1 designates a 45 rumble seat automobile, the rumble seat back 2 of which is shown in open position. The rumble seat cushion is designated by the reference numeral 3. Rumble seat cars are provided around the margins of the entrance of 50 the rumble seat compartment with a groove

4 which functions as a rain or moisture gutter, which gutter has an inner or rear upstanding flange 6, as shown in Figure 3.

55 My improved cape 7 may be made of any suitable material and consists of a top 8, side panels 9, and a rear panel 10, said top and panels cut to proper shape and size and then sewed, or otherwise secured together at their meeting edges.

60 The front end portion 8a of the sloping top 8 is provided with spring fasteners 11 for engagement with the rear flange or wall of the gutter 4 to secure such portion of the cape to the gutter. As shown, these fasteners 11 are placed a suitable distance apart and each fastener is formed of a single piece of spring metal and comprises a bracket arm 11a having upper and lower portions 11b and 11c bent at an angle to each other, the upper portion 11a being arranged to correspond to the slope of 65 the top 8 and riveted or otherwise secured thereto at a distance inwardly from the marginal edge 8b of said portion 8a. From this point of attachment of the arm the lower arm portion 11b extends downwardly and forwardly at an oblique angle and terminates in an upwardly bent inverted U-shaped clip 11c. This clip 11c lies above the horizontal plane of the lower end of the bracket arm portion 11c and comprises the front and rear gripping jaws 11d and 11e and the arched bight portion 11f, the said front jaw terminating in a supporting and stop bead 11g adapted to engage the bottom of the gutter 4 to limit the downward movement of the fastener therein. These clips are adapted to be snapped down in straddling engagement with the rear wall or flange of the gutter 70

75 80 85 fastener therein. These clips are adapted to be snapped down in straddling engagement with the rear wall or flange of the gutter with its jaws gripping said flange or wall to hold the cap portion 8a in position. As a result of this construction and mode of application of the fasteners the portion 8a of the cape is left free from connection with the fasteners to form a drain flap of the same degree 90

95 of thinness as the cape material and which may be draped over and supported by the bight 11f and bead 11g to depend loosely into the gutter 4 in spaced relation to the walls thereof, allowing rain water from the top of 100 the cape to drain into the gutter and prevent

ing it from flowing over the surfaces of the deck and into the rumble seat compartment. The back panel 10 is, or may be, designed to fit exteriorly of the back, as shown in Figure 5, so that the weight of the cape is carried by the clips 11 and the top edge of the back 2.

By this means the side panels 9 may be left unattached to the vehicle with their lower edges depending into the sides of the gutter, 10 as shown in Fig. 3, for drainage of moisture therefrom into the gutter.

The top panel 8 of the cape is provided with openings 12, through which the head and neck of the passenger projects and these openings 15 are provided with upstanding, but soft and pliable collars 13, which are provided with snap, or other suitable fasteners, 14 whereby when only one passenger is using the cape the other opening 12 may be closed against the 20 elements by a cap 15 having snap fastenings 25 which interlock with the fasteners 14.

To enable the passenger to quickly place the cape in operative position I provide a 25 slit, or opening, 16 extending from the collar 13 a suitable distance toward the front of the cape, as shown in Figures 2, 3 and 4, and to the edges of this slit I secure, preferably, the well known slide, or "Zipper" fastener 17 with the operating, or closing slide 18 within 30 the cape for ready manipulation by the passenger, and as a further closure for this slit I provide the flap 19, thus sealing the slit against the elements. It is, of course, understood that the collar 18 is open at the front in 35 alignment with the slit 16.

The cape may be folded and placed in the package 20, which package may be conveniently stored in the car, or it may be used as 40 a cushion.

I am aware that changes may be made in the construction of my cape illustrated without departing from the scope of the appended 45 claim.

What I claim is:

45 A combined cape and top for the rumble seat compartment in the rear deck of an automobile body provided with a rain gutter about the margins of the compartment, comprising 50 a cape cover for said compartment and the occupants thereof, said cover having an edge portion provided with inverted U-shaped spring fastening clips to engage the inner flange or wall of the gutter and fastening arms for the clips secured to the cover at a 55 point set back from the edge of the cover so as to leave a projecting part of said edge portion free to form a drain flap extending over the clips downwardly into the gutter in 60 spaced relation to the walls thereof.

In testimony whereof I affix my signature.

WILLIAM S. HAWKINS.
